ARTIFICIAL TOOTH

Edward M. Worhol, Houston, Tex.

Application March 19, 1932, Serial No. 599,877

2 Claims. (Cl. 32—9)

This invention relates to dental bridgework.

The mounting of artificial teeth between natural teeth usually includes the connection of a bridge or backing, of gold or its harder alloys to inlays, crowns, or other attachments carried by the abutment teeth. On this backing are mounted the necessary number of artificial teeth, which are made of porcelain.

The principal object of this invention is to provide a construction to render unnecessary the cutting of grooves or slots in, or tongues on, the porcelain tooth to an exact size. Such accurate cutting is difficult because porcelain is very easily chipped or fractured. In accordance with the present invention, very little machine work is done on the porcelain tooth itself, and this work may be done easily without chipping or fracturing the tooth. The accurate machine work is done on a metal connecting member connected to the tooth, and the metal backing on which the connecting member is mounted.

Another object is to provide a combined tooth and backing in which the connecting elements are remote from the gingival surface, to leave a substantial body of porcelain between the connecting elements and the gum, which portion may be ground to reduce the distance between the incisal edge or occlusal surface and the gingival surface, as desired.

The invention also has for its object the provision of a new and improved construction and combination of parts whereby the tooth will be rigidly and strongly supported on the backing, but may be quickly and easily removed from the backing without disturbing the connection of the backing to the abutment teeth.

Other objects will hereinafter appear.

The preferred embodiment of the invention in posterior teeth is illustrated by Figs. 1 to 6, inclusive, of the drawings; and in anterior teeth, by Figs. 7 to 13, inclusive.

Fig. 1 is a perspective view of a porcelain posterior tooth with a tube baked therein; Fig. 2, a similar view of said tooth with the metal connecting member mounted thereon; Fig. 3, a perspective view of the metal backing for said tooth; Fig. 4, a side elevation, partly in section, of the tooth and backing adjacent each other; Fig. 5, a partly sectional side elevation of the united tooth and backing; and Fig. 6, a side elevation of the tooth and backing on a gum.

Fig. 7 is a perspective view of a porcelain anterior tooth with the tube baked therein; Fig. 8, a perspective view of the metal backing; Fig. 9, a perspective view of said tooth with the metal

connecting member mounted thereon; Fig. 10, a diagrammatic view illustrating the connection of the artificial teeth to natural teeth; Fig. 11, a partly sectional side elevation of said tooth and backing adjacent each other; Fig. 12, a partly sectional side elevation of the united tooth and backing; and Fig. 13, a side elevation of the tooth and backing on a gum.

Referring to Fig. 1, the porcelain tooth is indicated at 1. It has a first lingual flat surface 2, extending from its occlusal surface, or biting edge 3, and a second flat surface 4 extending from said first surface 2 and inclined lingually therefrom. In the tooth 1 are a pair of sockets 5 opening at the first surface 2 and extending inwardly therefrom. These sockets 5 are enlarged inwardly for a purpose which will hereinafter appear. Within the tooth 1, opening at the surfaces 2 and 4 and extending inwardly therefrom is an internally threaded tube 6. The gingival surface 7 of the tooth is shaped to fit the gum 16 (Fig. 6).

Upon the surfaces 2 and 4 of the tooth is a connecting member 8, (Fig. 2) made of platinum, steel or the like, and having openings 9 and a tongue 10. The openings 9 are aligned with the sockets 5, and the tongue 10 is substantially dovetail-shaped. The connecting member 8 is connected to the tooth 1 by a screw 11, passing through the connecting member 8 and screwed into the tube 6.

The metal backing 12, shown by Fig. 3, is shaped to fit and to be coextensive with the surfaces 2 and 4, and has a pair of pins 13 to pass through the openings 9 in the connecting member 8 and into the sockets 5 in the tooth 1; and a groove 14 for the reception of the connecting member 8.

The mounting of the artificial posterior tooth just described between natural teeth is substantially the same as the mounting of the artificial anterior tooth, as shown by Fig. 10. In Fig. 10, anterior natural abutment teeth are indicated at 15, the roots thereof at 15a, the gum therebetween at 16, the backing at 30, and an artificial tooth at 18. This view illustrates the mounting of two artificial teeth between two natural teeth of the front portion of the lower jaw. One of these artificial teeth has been removed to illustrate its section of the backing. Backing 30 will comprise a single section or several sections, depending upon the number of artificial teeth to be mounted. These sections are soldered together, and the end sections are then soldered to crowns, inlays, or other metal attachments

carried by the abutment teeth to hold the bridge-work rigidly in place.

The method of making the posterior tooth just described is as follows:

5 Porcelain in paste form, is placed in a suitable mold having means to form the sockets 5 (Fig. 1) and to hold the metal tube 6 in place. The porcelain is subjected to heat, and after it is formed it is removed from the mold. It is then 10 subjected to a much higher temperature to fuse the porcelain. It is then permitted to cool, and the surfaces 2 and 4 are planed. This is all of the machine work that must be done on the porcelain tooth, and it may be done quickly and 15 easily without chipping or fracturing the porcelain.

The connecting member 8 (Fig. 2) is then applied to the surfaces 2 and 4 so that the openings 9 are aligned with the sockets 5. The screw 20 11 is then passed through the connecting member 8 and screwed into the tube 6.

Cement is then placed upon the surfaces 3 and 4 and in the sockets 5. The metal backing 12 (Fig. 3) having been soldered to the metallic parts of the bridge-work (as suggested by Fig. 10), the porcelain tooth 1, with the metal connecting member thereon, is moved into engagement with the backing 12 so that the pins 13 pass through the openings 9 in the connecting member 8 and into the sockets 5 into tooth 1, 30 and the tongue 10 of the metal connecting member 8 enters the groove 14 in the metal backing 12. The parts are then held together until the cement therebetween sets.

35 Should the porcelain tooth 1 be chipped or otherwise injured so that its removal is desired, the cement bond between the backing 12, member 8 and tooth 1 may be broken by moving the tooth on the backing. The tooth may then be 40 removed from the backing, the backing cleaned, and the new tooth cemented on the backing to take the place of the old. It will be noted that it is not necessary to disconnect the backing from the bridgework in order to replace the tooth.

45 Referring now to Figs. 7 through 13, inclusive, illustrating the anterior tooth, the tooth is indicated at 18. It has a first lingual surface 19 (Fig. 7), extending from its incisal or biting edge 20, and a second surface 21, extending from the first surface 19 and inclined lingually therefrom. In the tooth 18 opening at and extending 50 inwardly from the surface 19 is a socket 22. This socket is enlarged inwardly. Within the tooth 18, opening at and extending inwardly from the

surfaces 19 and 21 is a metal tube 23. The gingival surface of this tooth is indicated at 24. It is shaped to fit the gum 16, as shown by Fig. 13.

5 In Fig. 9, the metal connecting member is indicated at 26. It has an opening 27 aligned with the socket 22 and a tongue 28. The member 26 is held on the tooth 18 by a screw 29 passed through the member 26 and screwed into the tube 23.

10 The backing 30 (Fig. 8) has a pin 31 to pass through the opening 27 and into socket 22, and the groove 32 for the reception of the connecting member 26.

15 The making and mounting of the anterior tooth on its backing is the same as that of the posterior tooth above set forth.

The invention is not limited to the preferred embodiments herein described.

20 I claim:

1. The combination of a porcelain tooth having a first flat lingual surface extending from its biting edge, a socket opening at and extending inwardly from said first surface, and a second flat surface extending from said first surface and inclined lingually therefrom; a metal tube in said tooth opening at and extending inwardly from said lingual surfaces; a metal connecting member on said surfaces and having an opening aligned with said socket, and a tongue; a screw connecting said connecting member to said tube; and a metal backing coextensive with said surfaces and member and having a pin extending through the opening in said member and into the socket in said tooth, and a groove for the reception of the tongue of said member; said tube, member and backing being remote from the gingival surface of said tooth.

2. The combination of a porcelain tooth having two surfaces at an angle to each other, and a 40 socket opening at and extending inwardly from one of said surfaces; a metal tube in said tooth; a metal connecting member on said surfaces and having an opening aligned with the socket in said tooth, and a tongue; a screw extending through 45 said member and into said tube; and a metal backing coextensive with said surfaces and member and having a pin extending through the opening in said member and into the socket in said tooth, and a groove for the reception of the 50 tongue of said member; said tube, member and backing being remote from the gingival surface of said tooth.

EDWARD M. WORHOL.
